United States Patent

Des. 236,918
Patented Sept. 23, 1975

236,918

MEDICAL LIQUID BOTTLE

Charles J. McPhee, Sylmar, Calif., assignor to American Hospital Supply Corporation, Evanston, Ill.

Filed Feb. 26, 1974, Ser. No. 445,848

Term of patent 14 years

Int. Cl. D24—99

U.S. Cl. D83—1 U

FIG. 1.

FIG. 2.

FIG. 3.

FIG. 4.

FIG. 1 is a top plan view of a medical liquid bottle showing my new design;

FIG. 2 is a front elevational view thereof;

FIG. 3 is a right side elevational view thereof; and

FIG. 4 is a bottom plan view of FIG. 2.

I claim:

The ornamental design for a medical liquid bottle, as shown.
